UNITED STATES PATENT OFFICE.

FRANK P. MOSS, OF PHILADELPHIA, PENNSYLVANIA.

MAIL-BAG.

SPECIFICATION forming part of Letters Patent No. 374,845, dated December 13, 1887.

Application filed November 5, 1887. Serial No. 254,387. (No model.)

To all whom it may concern:

Be it known that I, FRANK P. MOSS, a citizen of the United States of America, residing at Philadelphia, in the county of Philadelphia and State of Pennsylvania, have invented certain new and useful Improvements in Mail-Bags; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in mail-bags; and it consists in the novel construction and arrangement of the locking-head therefor, which will be more fully hereinafter described, and pointed out 20 in the claims.

The object of my invention is to provide a mail-bag which will resist undue efforts to open the same and to extract letters therefrom, the parts thereof being simple and effective in their construction and operation, 25 strong and durable, easily handled, readily understood and operated, and cheap in manufacture. I attain these objects by the construction illustrated in the accompanying drawings, wherein letters of reference indicate 30 similar parts in the several views, and in which—

Figure 1 is a perspective view of a portion of a mail-bag with my improvement applied 35 in connection therewith. Fig. 2 is a rear elevation of the locking-plate. Fig. 3 is a top plan view of the head mechanism with one of the caps removed. Fig. 4 is a transverse section through the line $x-x$ of Fig. 2.

40 A indicates the mail-bag, which is constructed of the ordinary form and material generally used, having metallic head-plates B and B', which are riveted thereto. To each of said plates B and B' a folding metallic 45 hinged plate, C, is secured, to which the mail-bag is also attached by rivets, said plates C being adapted to fold inward, drawing the bag therewith.

The locking-plate B is constructed with a 50 head-plate, which provides a housing, and also with a front tag-frame, D', for the reception of destination-tags, and with a centrally-situated

hinged key-hole plate, D, which is pivotally swung at the point d to the lower portion of the plate B.

To the inner side of the plate B, and housed by the top cap thereof, two locking-bolts, E E, are mounted in suitable slotted guide-lugs, e' e'. One portion of each of the bolts E are reduced and encircled by coiled springs S, which bear 60 against the slotted lug e' adjacent thereto at one side, and against the inner end of the heads e, formed with said bolts. The extreme inner portion of each of the bolts E is formed with a downward angular extension, which is 65 slightly enlarged, and is bent to form projections d', which extend through the plate B on each side of the key-hole plate D, as shown in Fig. 1.

In rear of the key-hole plate D an annular 70 plate, D², is mounted, which contains the ordinary locking mechanism used in connection with the mail-bags. The upper portion of the said plate D² is formed with a bolt slot or aperture, d², which is engaged by the recessed bolt 75 b, projecting outward at an angle from the inner side of the plate B'.

At each end of the plate B' hollow bolts b' are secured, which are adapted to be pressed 80 into the locking-plate B and be engaged by the heads e of the spring-actuated locking-bolts E. It will be observed that the plate B' is a flat plate of slightly similar proportions 85 as regards length as the plate B, and is adapted to be pressed into the latter plate and inclosed thereby. When the said plate B' is inclosed within the plate B, the folding connecting-plates C are also folded inward, carrying the portion 90 of the bag attached thereto therewith. By this means it will be readily understood that 95 when the bag is locked the head will be entirely inclosed and pressed into the plate B, and thereby resist an attempt to abstract letters from the interior of the bag, for the reason that the upper portion of the bag is entirely closed and no ingress or opening left for the insertion of the hand or an instrument to obtain a grasp upon the mail within the bag.

The hinged plates C, when opened, tend to force and keep the mouth of the bag open, 100 thereby making it convenient for depositing mail therein.

When the plate B' is pressed into the locking-plate B, as hereinbefore set forth, the parts

are securely locked, first, at the ends, through the medium of the hollow bolts or staples b' engaging with the ends e of the spring-actuated bolt E , and are locked by spring action, 5 as will be readily understood. The key-hole plate D is then pressed up into place, and, being self-locking, is locked by closing, thus securing the recessed bolt b in the central portion of the plate B . The inner angular projecting ends of the bolts E extend through the plate B , and when the locking-plate D is pressed into locking position the projecting ends d' are thereby locked against movement 10 and cannot be operated until the said key-hole plate D is released from the plate B and allowed to drop down, as shown in Fig. 3. The two projections d' may then be engaged by the person unlocking the bag and pressed inward toward each other to release the ends of the 15 plate B from connection with the ends of the bolts E . By this means it will be seen that a double lock is provided, which cannot be operated to unloosen the head of the bag without first unlocking the key-hole plate D . This 20 provides double security against pilfering and increases the strength and durability of the bag, and the parts being of simple construction and operation, the manufacture thereof is comparatively inexpensive. The plate B is 25 also provided with a grip-strap, F , and with two end staples, b' , the purposes and uses of 30 which are obviously apparent.

The lock within the plate D^2 may be of any preferred form of construction best adapted 35 for the purpose.

Any minor changes which would not materially affect the construction of my improvement might be made and substituted for those shown and described without in the least departing from the nature and principle of my 40 invention.

The utility and adaptability of my improvement being obviously apparent, it is unnecessary to enlarge upon the same herein.

45 I claim—

1. The combination, with a mail-bag, of a self-locking plate containing spring-actuated bolts and a central locking and opposingly-

situated plate provided with a central recessed bolt and hollow end staples adapted to engage 50 with the locking mechanism in the locking-plate, and the hinged connecting-plates between the locking and rear plates, substantially as described.

2. The combination of the locking-plate having 55 top cap to form a housing therewith, the spring-actuated locking-bolts having inner angular projecting ends situated therein, the centrally-situated lock within said plate, the hinged key-hole plate, the opposingly-situated 60 plate having a central bolt and end staples, and the hinged connecting-plates between the said locking-plates, substantially as described.

3. The combination of a plate forming a 65 housing and containing spring-actuated sliding bolts and a centrally-situated positively-acting lock and hinged key-hole plate, tag-frames on each side of this plate, the rear opposingly-situated plate having hollow end staples adapted to engage with the spring-actuated bolts in 70 the locking-plate, the central bolt adapted to engage with the positively-acting lock centrally situated in the locking-plate, and the hinged connecting-plates between the bolt-plate and the locking-plate, all arranged as 75 and for the purpose set forth.

4. The combination of the locking-plate formed in a housing and having sliding bolts mounted on the inner side thereof with oppositely-situated heads and inner angular projecting ends which extend through the plate to the outside thereof, the hinged key-hole plate adapted to lock the inner angular projecting ends of the said bolts, as set forth, the rear plate carrying end staples and a central 85 bolt, and a hinged plate connecting the bolt-plate and the locking-plate, the said bolt-plate and hinged plates and a portion of the bag adapted to be housed within the locking-plate, 90 substantially as described.

In testimony whereof I affix my signature in presence of two witnesses.

FRANK P. MOSS.
